UNITED STATES PATENT OFFICE.

EDWARD ARTHUR SLACK, OF AUCKLAND, NEW ZEALAND.

TIE ADJUSTER AND RETAINER.

Application filed December 31, 1920. Serial No. 434,328.

To all whom it may concern:

Be it known that I, EDWARD ARTHUR SLACK, subject of King of Great Britain and Ireland, residing at 80 Grafton Road, 5 Auckland, New Zealand, have invented certain new and useful Improvements in Tie Adjusters and Retainers, of which the following is a specification.

This invention relates to devices on which 10 ties are made up and adjusted and by means of which said ties when made up are retained on collars without being passed around the latter.

The object of the invention is to provide 15 improvements in such devices, whereby they can be easily and securely attached to the collars and at the same time are enabled to be readily removed therefrom.

According to the invention the adjuster 20 and retainer which comprises a strip of thin celluloid, aluminum or other like material is formed with hook shaped ends adapted to enter and engage in slits in the collar near the ends of same.

25 The slits in the collar are located so that when the device is engaged therein the tie made up on the adjuster and retainer is held in its proper position at the front of the collar.

30 The device can be made in forms to enable the tie to be made up either in a sailors knot or as a bow.

In order to render the attachment of the device to the collar more secure and rigid, 35 means for fastening same to the front stud of the collar is provided.

The invention will be more particularly described with reference to the accompanying drawing in which:

40 Figure 1 is a perspective view of the front of a collar having secured thereon an adjuster and retainer the tie being removed.

Figure 2 is a rear view of an adjuster and retainer with a tie thereon made into a bow.

45 Figures 3 and 4 are a rear and an edge view respectively of a further form of adjuster and retainer suitable for the formation of bow ties.

The adjuster and retainer consists of a 50 strip 1 of thin light material curved and shaped to fit on the front of a collar 4 (Figure 1) and having hook shaped ends 2 adapted to enter and engage in slits 3 in the collar near the ends thereof. The ends 2 are 55 tapered as shown to facilitate their entrance into the slits 3.

The adjuster and retainer for use when a bow tie is to be made and worn, can be in either of the forms shown in Figures 2 or 3 the tie being made up thereon as shown 60 in Figure 2.

In the form shown in Figure 3 recesses 11 are provided and effectively prevent end movement of the device, the lower ends of the slits 3 engaging in the recesses. 65

Additional rigidity of the device on the collar is secured by attaching a strip 8 on the back of the strip 1, said strip 8 when the device is in position on the collar projecting downwards behind the head of the 70 front stud 8a.

Further means of attachment to the front stud consists of a strip 9 on the back of the strip 1 as shown in Figures 3 and 4 said strip 9 having a keyhole slot 10 in the centre 75 of its upper edge, adapted to pass upwards on the stud, at the same time as the ends 2 are inserted in the slits 3.

The forms of the device illustrated in the drawings can be used with single fold collars as well as with double collars, as the tie when made into a bow hides the adjuster and retainer and the slits 3. 80

What I do claim and desire to obtain by Letters Patent of the United States is:— 85

1. A tie adjuster and retainer comprising a body shaped to fit the front portion of a collar, supporting hooks carried by the terminals of the body adapted for insertion in slots formed in a collar, and collar button 90 engaging means carried by the body constituting supplemental supporting means for maintaining the body in position.

2. A tie adjuster and retainer comprising a body shaped to fit the front of a collar, 95 supporting hooks carried by the terminals of the body adapted for insertion in slots formed in a collar whereby to support the body in position thereon, and means carried by said body engageable beneath the head of 100 a collar button to assist the supporting hooks in maintaining the body in operative position.

In testimony whereof I have affixed my signature in the presence of two witnesses. 105

EDWARD ARTHUR SLACK.

Witnesses:

WILLIAM PINCHES,
MARY PICKINGLEN.
